UNITED STATES PATENT OFFICE.

STEPHEN J. ADKINS, OF FORT WORTH, TEXAS.

LOCK.

Application filed May 31, 1922. Serial No. 564,735.

To all whom it may concern:

Be it known that I, STEPHEN J. ADKINS, a citizen of the United States, residing at Fort Worth, in the county of Tarrant and 5 State of Texas, have invented a new and useful Lock, of which the following is a specification.

This invention aims to provide novel means for imparting sliding movement to a 10 locking bolt, in a lock, and to provide novel means for latching the bolt against movement.

In the drawings:—

Figure 1 shows in longitudinal section, 15 a device constructed in accordance with the invention; Figure 2 is a section on the line 2—2 of Figure 1; Figures 3 and 4 are transverse sections; Figure 5 is a perspective showing the locking bolt; Figure 6 is a 20 perspective showing the shaft and parts carried thereby.

In carrying out the invention there is provided a casing denoted generally by the numeral 1 and including a frame 2 and 25 side plates 3 and 4, the side plates having ears 5 received within the frame 2 and connected thereto by securing elements 6. The frame 2 has an inwardly projecting boss 7 carrying a guide spindle 8 slidably received 30 in a bore 10 formed in the inner end of a bolt 9 mounted to slide on the bottom of the casing 1, the bolt including a head 11 which is beveled as shown at 15, the bolt including, further, a foot 14, the numeral 12 marking an opening in the casing 1 wherein the 35 head 11 of the bolt 9 is slidably mounted.

The head 11 of the bolt 9 is provided with shoulders 16, and there are recesses 17 in the bolt, to the rear of the shoulders. Seats 40 18 are fashioned in the bolt at the ends of the recesses 17. The foot 14 of the bolt is provided with lateral projections 19. A helical compression spring 20 surrounds the spindle 8, one end of the spring abutting 45 against the boss 7, and the other end of the spring abutting against the foot 14 of the bolt to advance the bolt. The numeral 21 marks a bowed spring, the ends of which are received in the seats 18, the construction 50 of the upper edge of the bolt being duplicated on the lower edge of the bolt, as shown in Figure 5, to permit an axial reversal of the bolt.

The numeral 22 designates a shaft or the

like, journaled for rotation in bearings 23 55 on the side plates 3 and 4. The shaft 22 is provided with end portions 24 which may be rectangular in cross section, or of any other desired shape, the ends 24 of the shaft 22 being housed within the outer ends of the 60 bearings 23 as shown in Figure 4. Intermediate its ends, the shaft 22 is supplied with a hub 50, from which projects a latch 25. The hub 50 is supplied at its inner end with a cam 26. A stop 27 is mounted on the 65 side plate 3 of the casing 1.

A tubular shaft 28 is journaled for rotation in the side plates 3 and 4 and is provided with an opening 29 adapted to receive a spindle 30 carrying knobs 31. The shaft 70 28 has a depending arm 32, as shown in Figure 6, the arm 32 coacting with one of the projections 19 on the locking bolt 9. A slot 33 is formed in the arm 32, the slot defining a depending finger 34. A pivot 75 element 35 is mounted in the finger 34 and in the arm 32. One end of a link 36 is disposed between the finger 34 and the arm 32 and is carried by the pivot element 35. The other end of the link 36 is provided with an 80 opening 37 adapted to receive a pivot element 38 mounted in the upper end of a lever 39, fulcrumed intermediate its ends, as shown at 40, on the side plate 3. The lower end of the lever 39 is adapted to 85 cooperate with one of the projections 19 of the locking bolt 9.

When rotation is imparted to the shaft 28 by way of the spindle 30 and the knobs 31, the arm 32, cooperating with one of the 90 projections 19 on the locking bolt 9, will retract the locking bolt, against the action of the spring 20. When rotation is imparted to the shaft 28, in an opposite direction, through the instrumentality of the spindle 95 30, and one of the knobs 31, swinging movement will be imparted to the lever 39, through the instrumentality of the link 36, the lever 39 coacting with the corresponding projection 19 of the locking bolt 9. The 100 construction of the device is such, obviously, that, regardless of the direction in which the spindle 30 is rotated, the locking bolt may be retracted at the will of an operator.

After the locking bolt 9 has been advanced, 105 as shown in Figure 1, rotation may be imparted to the shaft 22, by a key or the like, applied to one of the ends 24 of the

shaft 22. When the shaft 22 is rotated, the latch 25 may be swung downwardly into the position shown in Figure 1, the latch cooperating with the corresponding shoulder 16 to prevent a retraction of the locking bolt. When it is desired to dispose the latch 25 in an inoperative position, as shown in dotted line in Figure 1, the latch may be swung upwardly and rearwardly, against 10 the stop 27, through the instrumentality of the shaft 22, the spring 21 cooperating with the cam or projection 26, to hold the latch in the dotted line position of Figure 1.

What is claimed is:—

15 1. In a device of the class described, a casing; a bolt slideable in the casing and provided in one edge with a shoulder, there being a recess in said edge of the bolt to the rear of the shoulder; a bowed spring in 20 the recess and engaged at its ends with the bolt at the ends of the recess; spring means for advancing the bolt; means under the control of an operator for retracting the bolt; a shaft journaled in the casing; a latch 25 carried by the shaft and coacting with the shoulder to hold the locking bolt advanced; and a cam on the shaft, the cam coacting with the spring, intermediate the ends of

the spring, to hold the latch out of engagement with the shoulder. 30

2. In a device of the class described, a casing; a bolt mounted for sliding movement in the casing and provided on its opposite sides with projections; spring means for advancing the bolt; a shaft journaled in the casing; an arm carried by the shaft and cooperating with the projection on one side of the bolt to retract the bolt when the shaft is rotated in one direction; a lever fulcrumed intermediate its ends on the casing, between the shaft and the bolt, and cooperating at one end with the projection on the other side of the bolt to retract the bolt when the shaft is rotated in an opposite direction; and a link forming a connection 45 between the arm and the other end of the lever and disposed, in approximate parallelism to the bolt, between the shaft and the fulcrum of the lever.

In testimony that I claim the foregoing as 50 my own, I have hereto affixed my signature in the presence of two witnesses.

STEPHEN J. ADKINS.
